CLAIM

The ornamental design for an electrical connector, as shown and described.

DESCRIPTION

The present article relates to connectors employed for electrical signal-connections between respective electronic devices, which are fixes in electronic devices including audio-visual equipment such as video cameras, video decks, televisions and personal computers.

FIG. 1 is a front elevation view of an electrical connector showing my new design;

FIG. 2 is a rear elevation view thereof;

FIG. 3 is a top plan view thereof;

FIG. 4 is a bottom plan view thereof;

FIG. 5 is a left side view thereof; and,

FIG. 6 is a right side view thereof.
